SHOWER OR SPRAY BATH APPARATUS

Filed April 23, 1928

Inventor

Rupert Livingston Frost,

3 John Lewis Jones,
Attorney.

UNITED STATES PATENT OFFICE.

RUPERT LIVINGSTON FROST, OF CINCINNATI, OHIO.

SHOWER OR SPRAY BATH APPARATUS.

Application filed April 23, 1928. Serial No. 272,178.

This invention relates to readily detachable and adjustable shower and spray attachments for convenient service use in bath-tubs and other suitable available vessels in cleansing

5 the person, and an important object thereof is to provide special ring shower or spray means that are adjustably mounted or clamped on a supporting upright rod or standard in vertically-slidable position convenient

10 to the water supply and adapted to suit the height of the person using the tub, whether tall or short, or whether seated or standing therein, and, also, using such ring shower or spray means to form a suspension-

15 holder for a splash guard or protecting curtain, and aiming always to avoid wetting the head, if desired, as well as to adapt the device to adult and child use alike, and with or without direct means of attachment to the

20 tub; and another object of the invention is to provide a rose-spray that is vertically slidable on said upright supporting standard or rod so that the water may be concentrated in various desired places on the person. Other

25 features of the invention will be fully referred to by me in the accompanying sheet of drawings, in which—

Figure 1 is a fragmentary perspective view of a bath-tub in connection with which I have 30 shown my improved vertically adjustable shower-ring and rose-spray devices, adapted to be operated independent of each other by the bather in the tub; Fig. 2, a bottom-plan view of the said shower-ring and its clamping

35 means; Fig. 3, an end elevation of my apparatus showing the shower-ring and the clamping-means in supported-place in connection with a tub of any suitable construction, the said ring being used for adjustably suspending

40 a drop-curtain from the vertical wall-rod, and a stool, together with a vapor-lamp being shown in dotted-lines for displaying my device when used for vapor or steaming purposes; Fig. 4, a view similar to Fig. 3, but

45 showing my shower-ring and a drop-curtain suspended from a vertical wall-rod for use in connection with an ordinary wash or general utility tub and adapted to be connected-up by means of a flexible tubing with a water

50 vessel that is supported on a wall-shelf above the said shower-ring to give proper gravity or head-pressure to the fluid in said vessel for discharge through the said shower-ring on the person or bather in said tub; and Fig. 5,

55 a transverse section of an ordinary roll-edge bath-tub showing the manner in which a rose-

spray device may be adjustably supported on a vertical rod or standard that is detachably secured to the roll-edge of the tub at any point convenient to the bather in using the 60 said spray, and said standard having a drop-curtain ring or yoke at its upper end for suspending the curtain in proper position over the tub or below its upper edge in connection with the bather, either sitting or standing 65 therein.

An ordinary partly built-in bath-tub A is shown in Fig. 1, together with a section of floor B and a section of tile or other suitable wall C, all in due relation for use in connection with the customary end-faucet. 70

6 indicates a vertical rod or standard attached by means of brackets 7, 7, to the said wall C above the rear edge of the tub A, about mid-length of the latter, for the convenient 75 use or service of the bather.

8 indicates a tubular shower-ring having its jet-openings 9 in a circular series along its lower inner periphery so as to direct the flow of the water at an angle or inclination downwardly toward the body of the bather and preferably without the water contacting with his head. This ring is constructed almost a full circle, with its opposite ends 10 and 11 bent downwardly at a right-angle for detachable engagement with a flexible rubber-tubing 12 that leads to the neutralizing discharge-part 13 of the usual double-valve faucet 14 from the pendent end 11, the other

80 pendent end 10 of the said ring being provided with a removable screw-plug (not shown) for reversing the position of the attaching end of the water-supply tubing 12 when it is desired to reverse the flow of the water through the ring in keeping the jet-openings 9 clear or to suit the position of the 85 said faucet in the tub. Both of said downturned ends 10 and 11 are adapted to the use of a screw-plug in their open orificed extremities.

90 The said ring 8 is detachably and adjustably supported, for vertical slidable-motion, on the said vertical rod or standard 6 by means of a clamp that is composed of a pair of jaws 15 and 16 that are hinged together at 17 and have a pair of coinciding lugs 18 and 19, disposed inwardly for the convenience of the bather, and one of which lugs (18) is internally screw-threaded for the engagement of the like threaded end of 95 a lug-closing draw-screw 20 which has a handle 21, the form and structure of such

100

105

110

clamping device being best shown in the bottom-plan, Fig. 2. By manipulating the handle 21 the clamp can be readily opened and closed to and from contacting-engagement 5 with the standard 6 in raising and lowering the shower-ring along said standard for vertically varying the direction and position of the discharging water along the person of the bather, especially when in a standing position 10 in the tub, and, also, readily allowing for his sitting position, as desired. The clamping device which forms a coupling for the ring can be readily thrown wide open for the removal of itself and the ring simultaneously 15 from the rod 6 by withdrawing the screw 20 that can be accomplished by sliding the handle 21 in its head 21^a, or the ring can be removed from the clamp by withdrawing the bent hook-ends 10 and 11 from the jaws 20 after first removing the rubber tubing from one of them to which it has been connected. Thus the entire shower-ring device is quite portable and its supporting standard 6 can also be easily removed from the wall for packing 25 in small compass therewith.

The rose-spray device 22 has a hollow coupling-shank 23 that extends downwardly through a vertical hole in the outer end of a thumb- and - finger spring - compression 30 clamp-jaw 24, the latter having due clamping engagement with the rod 6, for up-and-down sliding movement of the rose-spray to suit the place of discharge of the spray on the body of the bather, or on his head, 35 if desired. The said clamp holds the rose-spray in adjusted position wherever placed on the standard, ready for easy detachment or vertical movement of the spray. A rubber tubing 25 is connected to the lower open 40 end of the hollow fluid coupling-shank 23 for connection with the faucet.

It is obvious that either of the shower-ring or rose-spray devices can be mounted and used separately, or either one can be 45 retained on the standard 6 without the presence of the other, just as the bather desires and plans, and, furthermore, an ordinary wash-tub D, such as is shown in Fig. 4, can be used instead of the forms of bath-tub seen in Figs. 1 and 5, a vertical rod or standard 50 6 being attached to the side wall, adjacent the plain wash-tub and having a shower-ring 8 clamped in removable and sliding place thereon by means of a jaw device similar to that seen in Figs. 1 and 2 and a drop-curtain F used on the said ring 8 for confining the sprayed water within the radius of the tub that receives it from the surface of the bather whence he gets it through the rubber tubing 55 12 from discharge-connection at the bottom of a bucket or vessel 26 that is supported by a bracketed shelf on said side wall above the standard 6, such bucket being duly elevated above the level of said shower-ring so as to 60 give the proper gravity or head-pressure to

the supply or stream of water flowing from the bucket to the said shower-ring.

The form of device seen in Fig. 4 is especially well adapted for use in remote or outlying places where there is ordinarily no 70 pumped or pipe-conducted water supply.

The form of device seen in Fig. 3 is the one adapted for use as a vapor bath and not necessarily coupled-up with a water supply for spray or shower purposes, and in which 75 event the ring 8 is not a perforated one but simply a plain ring or yoke that is removably and adjustably held on the standard 6 by means of a clamp device similar to the one seen in Fig 2, or the clamp may be the 80 same as that seen in Figs. 4 and 5. A curtain E is used on the ring 8 for drop-suspension in the tub D which may be either a bath tub or an ordinary plain general utility or wash tub, and a stool G (shown dotted) is placed in the tub for the bather to 85 sit upon while the vapor from a heating-lamp H (also shown dotted) beneath the said stool is arising around said bather whose shoulders are covered with a bath-towel or other suitable cloth, in the usual 90 vapor-bath service, to confine said vapor within the chamber thus afforded by the said suspended drop-curtain that can be readily adjusted up or down on said standard 6 to suit his height above the tub bottom. 95

In Fig. 5 I show how the upright ring-supporting standard 6 can be mounted by means of a clamp-member 27 on the roll-edge 28 of a bath-tub, with an intervening rubber pad 29 to protect the enameled surface of said roll-edge, and, also, with a setscrew 30, the latter working from beneath the clamp-member, for contact with the underside of said roll-edge, to hold the standard 6 in vertical or upright position at any desired point along the said roll-edge of the tub, but preferably convenient, of course, for the rubber hose connection 25 of the rose-spray 22 that is detachably and adjustably supported by means of an ordinary thumb-and-finger spring-controlled clamp 24 on 100 said ring-rod 6, the supporting-ring for a drop-curtain being shown at 8 and duly clamped or held on the rod 6 for adjustable positioning, as in the forms seen in Figs. 1, 3 and 4. Thus it will not be necessary to mount the said rod or standard 6 on the side wall of the room, which would be objectionable and inconvenient in many instances and not so handy to place or remove as on and along the edge of the tub. 110

I claim:—

1. In a shower or spray device for bath-tubs or the like, the combination of a horizontal shower and curtain-supporting ring, an upright supporting-standard, a pair of clamping-jaws pivotally hinged together in shiftable relation on said standard, hand- 120

operated means for locking said clamping-jaws in the said shiftable relation and adapted to be readily detached therefrom, and tubular means for supplying bathing fluid to said shower and curtain-supporting ring.

2. In a shower or spray device for bathtubs or the like, the combination of an auxiliary rose-spray having an extensible wa-
10 ter-supply connection, an upright standard and a hand-operated clamping-jaw adapted

to be removably and adjustably held in variable using place on the said standard and to variably support the said auxiliary rose-spray on the standard or to permit it to be 15 readily detached therefrom and thence held in the hand of the bather for movable use, as required.

In testimony whereof I hereunto affix my signature.

RUPERT LIVINGSTON FROST.
